UNITED STATES PATENT OFFICE.

PAUL GROEBER, OF NEW YORK, N. Y.

DESIGN FOR WALL-PAPER.

SPECIFICATION forming part of Design No. 15,067, dated June 17, 1884.

Application filed April 11, 1884. Term of patent 21 years.

To all whom it may concern:

Be it known that I, PAUL GROEBER, a citizen of the United States, residing in the city of New York, county and State of New York, 5 have invented and produced a new and original Design for a Wall or Ceiling Covering, which is especially intended as a frieze, of which the following is a specification.

The drawing represents a front plan view of 10 the design.

This design is composite in its character, being partly in the Egyptian and partly in the Eastlake style. The leading features are a two-handled vase, a, with ornamented base 15 resting on the lower border of the design, and springing from the mouth of the vase are two S-like scrolls, b b. Immediately above the scrolls is placed an ornamented rosette, c, encircled, except at the base, by a narrow band, 20 d, radiating from which are thirteen leaves treated in the Egyptian style, six of them, e, typical of fans, and seven of them, f, typical of spear-heads. On the right and left are wing-shaped ornaments g, with bands, beads, 25 and volutes. These rest on a horizontal band, h, represented as being in front of the vase, and which is decorated with rosettes. The whole of the before-mentioned configuration is arranged within a circular space bounded 30 by scrolls l, gracefully ornamented with foliates and volutes.

The design on the right and the left of the wing-shaped figures g is alike, and consists of a broad band, k, with beaded border leading 35 horizontally to a large rosette, l, with smooth center button. A second rosette, m, is also placed obliquely above the last rosette, fitting in the upper portion of the design. These rosettes are semicircular in form, the bisected edge being bounded by two leaflets, n n, which 40 appear to overlap the rosette.

The whole of the interstices of the design so far described is filled in with a finely-beaded groundwork, o.

The design has an upper and lower border, 45 p p, each consisting of a molding in three sections, the center being ornamented with plain rosettes placed at equal distances, having a center button. A second molding ornamented with arrow-headed leaves placed at equal distances forms the boundary to the central portion of the general design.

This design shows that by judicious treatment two very opposite styles may be blended with perfect harmony, producing an effect 55 which is in accord with art principles and agreeable to the eye.

I claim—

The design herein described and shown, consisting of the vase-like figure resting on or near 60 the lower border, a rosette placed above the vase, surrounded with fan and spear-head shaped figures arranged circularly, a horizontal band placed in front of the vase, and wing-shaped figures springing from it inclosing 65 by their upper portion the fan and spear-head shaped bodies, scrolls at the top and bottom of the design inclosing the central figures, and broad horizontal bands extending to the right and left, which connect the central portion of the design with laterally-located rosettes, the remainder of the design being filled up with scrolls, rosettes, and like ornamental figures, and an upper and lower border.

PAUL GROEBER.
